US0D1029023S

(12) **United States Design Patent** (10) Patent No.: **US D1,029,023 S**
Konishi et al. (45) Date of Patent: ** May 28, 2024

(54) **DISPLAY SCREEN WITH GRAPHICAL USER INTERFACE**

(71) Applicant: **Hitachi High-Tech Corporation**,
 Tokyo (JP)

(72) Inventors: **Yayoi Konishi**, Tokyo (JP); **Fuka Matsudaira**, Tokyo (JP); **Masaki Takano**, Tokyo (JP); **Masataka Okayama**, Tokyo (JP); **Hideki Watanabe**, Tokyo (JP); **Jin Shimizu**, Tokyo (JP)

(73) Assignee: **Hitachi High-Tech Corporation**,
 Tokyo (JP)

(**) Term: **15 Years**

(21) Appl. No.: **29/780,374**

(22) Filed: **Apr. 23, 2021**

(30) **Foreign Application Priority Data**

Oct. 26, 2020 (JP) ..... 2020-023078 D
 (51) **LOC (14) Cl.** **14-04**
 (52) **U.S. Cl.**
 USPC **D14/486**
 (58) **Field of Classification Search**
 USPC D14/485-495
 CPC G06F 3/048-04897
 See application file for complete search history.

(57) **CLAIM**

The ornamental design for a display screen with graphical user interface, as shown and described.

DESCRIPTION

The sole FIGURE is a front view of a display screen with graphical user interface according to the design.

The outermost broken line rectangle illustrates the display screen. The remaining broken lines, including all text shown, illustrate portions of the graphical user interface. None of the broken lines form part of the claimed design.

1 Claim, 1 Drawing Sheet
